MEMORIAL TABLET.

No. 19,264.

Patented Aug. 13, 1889.

UNITED STATES PATENT OFFICE.

JOHN W. DOWLING, OF EVANSTON, ILLINOIS.

DESIGN FOR A MEMORIAL TABLET.

SPECIFICATION forming part of Design No. 19,264, dated August 13, 1889.

Application filed April 26, 1889. Serial No. 308,723. Term of patent 14 years.

To all whom it may concern:

Be it known that I, JOHN W. DOWLING, a citizen of the United States, residing at Evanston, county of Cook, and State of Illinois, have 5 invented and produced a certain new and original Design for a Memorial Tablet, of which the following is a specification, reference being had to the accompanying photographs, forming a part thereof.

- 10 The features of this design consist in the ornamental emblematic figures which appear upon the body or ground of the border of the tablet. These emblematic features are, first, the figure of a cross upon a background of 15 divergent rays at the center of the top border of the tablet; second, a chalice encircled by a conventional wreath composed of two symmetrical parts united at the bottom underneath the chalice and terminating a short 20 distance apart above the open top of the chalice, this figure being located at the middle of the bottom border of the tablet; third, symmetrical figures, one at the right and the other at the left side of the border and occupying 25 the upper half of the side border, said figures each consisting of a conventional representation of a dove with spread wings carrying a suspended lamp conventionally represented as aflame and emitting divergent rays; 30 fourth, a vase containing a bunch of calla lilies, conventionally known as the "Virgin lily," this figure occupying the lower half of one side border; fifth, a vase containing a spray of the flower known as the "St. Joseph lily," or "lily of the field," conventionally represented, this figure occupying a position similar to that occupied by the vase of calla lilies on the opposite side border of the tablet. 35

I claim—

The design for a memorial tablet herein 40 shown and described, characterized by the ornamental figures appearing on the body or ground of the border, comprising the conventional representation of an illuminated cross at the top, a conventional representation of 45 an enwreathed chalice at the bottom, conventional representations of flying doves carrying lamps aflame at the upper part of the side borders, and conventional representations of the Virgin lily and the St. Joseph lily at the 50 lower part of the opposite side borders, substantially as described.

In testimony whereof I have set my hand, in the presence of two witnesses, at Chicago, Illinois, this 20th day of April, A. D. 1889.

JOHN W. DOWLING.
